(57) **CLAIM**

The ornamental design for a jewelry stone setting, as shown and described.

DESCRIPTION

FIG. 1 is a top perspective view of a jewelry stone setting showing my new design;

FIG. 2 is a top plan view thereof;

FIG. 3 is a left side elevation view of the jewelry stone setting, the right side and opposite side views being identical;

FIG. 4 is a cross-sectional view of the jewelry stone setting taken through line 4-4 of FIG. 2; and,

FIG. 5 is a bottom plan view of the jewelry stone setting shown in FIG. 2.
